(No Model.)

T. KUNDTZ.
TABLE OR CABINET FOR SEWING MACHINES.

No. 588,798.

Patented Aug. 24, 1897.

UNITED STATES PATENT OFFICE.

THEODOR KUNDTZ, OF CLEVELAND, OHIO.

TABLE OR CABINET FOR SEWING-MACHINES.

SPECIFICATION forming part of Letters Patent No. 588,798, dated August 24, 1897.

Application filed January 2, 1896. Serial No. 617,694. (No model.)

To all whom it may concern:

Be it known that I, THEODOR KUNDTZ, of Cleveland, Cuyahoga county, Ohio, have invented certain new and useful Improvements 5 in Tables or Cabinets for Sewing-Machines, &c.; and I do hereby declare the following to be a full, clear, and exact description of the invention, such as will enable others skilled in the art to which it pertains to make and 10 use the same.

My invention relates to improvements in cabinets or tables for sewing-machines, &c., wherein the sewing-machine head or other machine is mounted upon a leaf that in the 15 elevated or operative position of said machine is flush with the top of the table or cabinet and is tilttable downwardly below said top.

The invention consists in certain meritorious and novel features of construction here- 20 inafter described, and pointed out in the claims.

In the accompanying drawings, Figure I is a top plan of a sewing-machine table or cabinet embodying my invention. Portions are 25 broken away and in section in this figure, and the tilting leaf that bears the sewing-machine head is in its elevated position. Fig. II is a rear side elevation of the same. In this figure the sewing-machine head and the leaf sup- 30 porting it are in solid lines shown in their lower or downwardly-tilted position, and the lifting-leaf that is employed in elevating the sewing-machine head is in dotted lines shown in two other positions. Fig. III is a vertical 35 section of a portion of the top of the table or cabinet and shows the leaf B in its elevated and horizontal position, and shows also the slides K and P, that are instrumental in supporting said leaf and the latter's load, and 40 shows also the operative connection between said slides.

Referring to the drawings, A designates the supporting frame or stand of the table or cabinet, and a represents the top of said 45 cabinet or table. Top a is provided with a centrally-located rectangular opening a'. Opening a' is designed to receive and be closed by the tilting leaf B, that bears the sewing-machine head C or other machine or 50 object. Leaf B at each end is pivoted at b horizontally and longitudinally to top a, and leaf B is consequently capable of tilting verti-

cally: The sewing-machine head is lowered by tilting said leaf downwardly, and said head is actuated from its lower position into 55 its operative or elevated position by tilting leaf B upwardly into opening a' and flush with top a.

A folding leaf D is hinged horizontally and transversely of the table to the left-hand end 60 of the top a. Said folding leaf is operatively connected with the leaf that bears the sewing-machine head and is adapted to cover the opening a' and cover the sewing-machine head when said head is in its downwardly-tilted 65 position. When head C is in its elevated position, as shown in dotted lines, Fig. II, leaf D is flush with the top a, as shown in the second dotted position of said leaf in said figure. Said leaf D is designed to lift leaf B 70 and its load from the latter's downwardly-tilted position, and consequently such connection between said leaves is provided as will render the load-bearing leaf B capable 75 of being lifted by leaf D during the time that the latter is being tilted from its closing position into the position wherein it is flush with top a.

One object of my invention is to provide 80 such connection between leaves D and B that leaf D will not begin to lift until it is about in a perpendicular position, as shown in the first dotted position in Fig. II, and thereby not only facilitate the elevation of the sewing-machine head, but reduce the work at- 85 tached to the elevation of said head to a minimum.

My improved operative connection between leaves B and D comprises a chain E, that is securely attached at one end to and at or near 90 the rear edge of leaf D, a short distance from the axis of said leaf. Chain E extends from its point of attachment to leaf D over the left-hand end of the rear portion of the top a of the cabinet or table, and leads over a sheave 95 G, arranged longitudinally of said top and supported within a slot a², formed in said portion of the top, and chain E leads through the aforesaid slot and downwardly from the sheave to and in under a sheave H, that is ar- 100 ranged at right angles to and below sheave G and is fixed upon the left-hand end of a horizontally-arranged shaft h, supported from and below the rear portion of top a. Chain

E, in the closing position of leaf D, is slack and hangs below sheave H and is attached to the rear side of said sheave. Another sheave h' is fixed upon the right-hand end of shaft 5 h, and a spiral spring I, that has one of its ends attached at I' to the rear side of said sheave h', leads in under and forwardly from the sheave, and has its opposite end attached at I² to the under side of the top a of the table or cabinet. Said spring counterbalances the sewing-machine head, and thereby facilitates the elevation of said head from its lowered position. Shaft h at its central portion has a forwardly-projecting arm h², that extends in under and transversely of the under side of the sewing-machine head and the leaf that carries said head, and lifts said head and leaf from their lower position upon the rearward oscillation of shaft h, effected by the required movement of leaf D. Chain E is slack, while leaf B and the sewing-machine head supported therefrom are in their downwardly-tilted position, as already indicated, and the length of said chain and the arrangement of 25 parts are such that the slack in said chain will be taken up and leaf D shall commence to lift when said leaf is about in a perpendicular position, as shown in the first dotted position of said leaf in Fig. II, so that the work 30 attached to the lifting of the sewing-machine head is reduced to a minimum.

Mechanism instrumental in holding the forward portion of leaf B and its load in the elevated position and assisting the aforesaid lifting means in holding the load elevated comprises, preferably, two small plates or slides arranged to slide longitudinally within opposite ends, respectively, of top a. Slide K is arranged to move endwise of a mortise a³ in 35 the left-hand end of top a and in under the left-hand end of leaf B. In its normal position this slide K is out of engagement with leaf B and, as shown in Fig. II, protrudes beyond the left-hand edge of top a, and hence 40 leaf D, when it is actuated into line with top a, actuates slide K inwardly in under leaf B, as shown in Fig. I. A forwardly and rearwardly extending and horizontally-swinging and centrally-fulcrumed lever L has its rear 45 end operatively connected with slide K and has its forward end attached to the left-hand end of a link M, arranged horizontally below and longitudinally of the forward portion of top a. The right-hand end of link M is operatively connected with the central portion 50 of a forwardly and rearwardly extending horizontally-swinging lever O, supported from the right-hand end of top a. Lever O is fulcrumed at its forward end and has its rear end operatively connected with a slide P, that is arranged to slide from within a mortise a⁴ in the right-hand end of top a in under the right-hand end of leaf B, and that, in the normal position of the slide K, is out of engagement 55 with leaf B. Slides K and P coöperate, and the arrangement of parts are such, therefore, that when slide K is moved in under the left-

hand end of leaf B slide P is actuated under the right-hand end of said leaf. The under side of leaf B is preferably cut away somewhat, as at B', where it is engaged by slides K and P in its upwardly-tilted position. 70

A forwardly and rearwardly extending leaf-spring J, attached at its rear end at J' to the top a within a recess or mortise a⁵ in the under side of the left-hand end of said top, has its forward end engaging a shoulder K', formed upon slide K, and acts to retain slides K and P and the mechanism connecting said slides in their inoperative position. Said spring therefore actuates said slides and mechanism into their inoperative position immediately upon closing the lifting-leaf D down over the lowered sewing-machine head. 75

Slides K and P, the mechanism operatively connecting said slides with each other, the mortises or recesses a³, a⁴, and a⁵, and the spring J are, it is believed, sufficiently illustrated in dotted lines, Fig. I, and their operation will be readily understood without further description or illustration. 80

I would also remark that member h² does not in the case illustrated directly engage the sewing-machine head or the load-bearing leaf, but engages a metallic rod or bar R, that extends in under and longitudinally of said head and is secured at its ends to the under side of leaf B, as shown in Fig. II, and this construction I prefer. 95

What I claim is—

1. In combination with the top of the table or cabinet, which top is provided with a vertical opening a', the load-bearing tilting leaf B arranged to close said opening in its upwardly-tilted position, and the lifting-leaf D hinged to the left-hand portion of said top, of an oscillating shaft suitably supported below the rear portion of the top and having an arm or member overlapping the under side of the load-bearing leaf, mechanism arranged to oscillate said shaft and operatively connected with the lifting-leaf, and the arrangement of parts being such that the load-bearing leaf is lowered or elevated according as the lifting-leaf is tilted into the one or the other of its extreme positions, substantially as set forth. 100

2. The combination with the top of the table or cabinet, which top has a vertical opening therethrough, the suitably-supported tilting load-bearing leaf arranged to close said opening in its upwardly-tilted position, and the lifting-leaf D hinged to the left-hand portion of the top and arranged to close down over the tilting load-bearing leaf in the latter's downwardly-tilted position, of an oscillating shaft h suitably supported below the rear portion of said top and having an arm or member h² extending in under and arranged to lift or carry the load-bearing leaf, the sheave H, the guide-sheave G, the chain E, the sheave h' and the counterbalancing-spring I, all arranged and operating substantially as shown, for the purpose specified. 105

3. The combination with the top of the table or cabinet, which top has a vertical opening therethrough and has the mortises or recesses a^3 , a^4 and a^5 , and the suitably-supported tilting load-bearing leaf arranged to close said opening in its upwardly-tilted position, of the slides K and P arranged to be capable of movement in under opposite ends, respectively, of the aforesaid leaf, lever mechanism operatively connecting said slides with each other, the actuating-leaf D hinged to the left-hand end of the aforesaid top, the spring J' operatively engaging one of said slides and acting to retain the slides and connecting

mechanism in their inoperative position, and 15 the arrangement of parts being such that in their normal position one of said slides shall protrude outside of the top in position to be engaged and actuated by the said hinged leaf and both of the slides shall be operated simultaneously, substantially as set forth.

In testimony whereof I sign this specification, in the presence of two witnesses, this 31st day of December, 1896.

THEODOR KUNDTZ.
